Application April 14, 1949, Serial No. 1,986

Term of patent 3½ years

(Cl. D58—12.6)

To all whom it may concern:

Be it known that I, Thomas D'Addario, a citizen of the United States of America and a resident of the city of New York, county of New York, and State of New York, have invented a new, original, and ornamental Design for a Game Box Top, of which the following is a specification; reference being had to the accompanying drawing, forming a part hereof, wherein:

The figure is a top plan view of a game box top, showing my new design.

The nature of the article is substantially thin and flat.

I claim:

The ornamental design for a game box top, substantially as shown and described.

THOMAS D'ADDARIO.
